AIR OPERATED TOY

Filed Jan. 20, 1928

INVENTOR
JOHN M. ABRAMS
BY Morris & Nolte
ATTORNEY

UNITED STATES PATENT OFFICE

JOHN M. ABRAMS, OF BROOKLYN, NEW YORK

AIR-OPERATED TOY

Application filed January 20, 1928. Serial No. 248,030.

This invention relates to toys, but more particularly to a combination toy and whistle designed for the amusement of children, and the object is to produce a toy which may be manufactured and sold at a moderate price, and which will not be easily broken or injured in use.

It is an object of the invention to combine with a whistle a revolving wheel adapted to be propelled by air blown through the whistle, the wheel being provided with a picture or representation of an animate creature arranged to appear to perform some entertaining act as the wheel rotates.

Other objects and advantages will herein-after appear.

In the drawings forming part of this specification:

Figure 1 is a side elevation of a toy embodying features of the present invention;

Figure 2 is a plan view of the toy;

Figure 3 is a fragmentary, longitudinal, vertical section showing a portion of the wheel;

Figure 4 is a vertical section taken on the line 4—4 of Figure 1, looking in the direction of the arrows;

Figure 5 is a fragmentary, longitudinal, vertical section showing the wheel and whistle structure;

Figure 6 is a side elevation of another embodiment of the invention; and

Figure 7 is a transverse, vertical section taken on the line 7—7 of Figure 1, looking in the direction of the arrows.

The toy comprises three principal parts, namely, a whistle 1, a revolving wheel 2, and a member 3 connecting the whistle and the wheel, and providing a bearing for the wheel.

The air blown through the whistle is effective to rotate the wheel in a counterclockwise direction, as seen in Figure 1, as will be more fully brought out. The whistle comprises a mouth-piece 4, a blow tube 5, a reed holder 6, and a reed 7.

In order to assure the passage through tube 5 of sufficient air to rotate the wheel, the reed holder 6 is positioned in the upper part of the tube, and the lower part of the tube is left unobstructed. The reed holder 6 is

turned upward and formed to fit and close the upper portion of the delivery end of the tube, so that all of the air blown into the tube is discharged through the lower part of the tube directly against the wheel 2. For securing 55 the reed holder in place, provision is made of internal projections or ribs 8 in the tube 5, which support the reed holder and cause it to fit snugly in place.

The connecting member 3 is secured upon 60 the delivery end of tube 5. This member is desirably made of a single sheet of material, such as cardboard, and comprises a sleeve portion 9 which is wrapped around the tube 5 and adhesively secured thereto, and downwardly extending body portions 10 and 11 which embrace the wheel 2 and terminate below the center thereof.

In the illustrative embodiment of Figure 1 the body portion 10 has pictured thereon the 70 head and trunk of a foot-ball player with his arms extended, and a foot-ball held in his hands, as if he were about to kick it. The body members 10 and 11 are perforated near the lower ends thereof to provide a bearing 75 for the wheel 2. A tubular bearing and spacing member 12 may be interposed between the members 10 and 11, and a hollow rivet 12^b may be passed through the member 12 and have its ends upset against the outer 80 faces of body members 10 and 11. This device constitutes both a spacing and connecting means for the body members 10 and 11 and a bearing for the wheel 2.

The wheel 2 comprises two cardboard discs 85 13 and 14 having bearing eyelets 12^a secured at the centers thereof for reception of the bearing 12. The disc 13 has pictured thereon a leg of a foot-ball player, completing the picture on the body member 10.

The discs 13 and 14 are secured to one another in spaced relation by a band 15 of cardboard which is adhesively secured by flaps or flanges 16 with the discs 13 and 14. This strip 15 is circular, being of somewhat less 95 diameter than the discs, and is concentric with the discs. The strip 15 has its opposite ends brought together and adhesively secured in overlapping relation.

As indicated in Figures 1 and 3, the over- 100

lapped ends of the strip 15 are situated in line with the foot-ball player's leg pictured on the disc 13. The overlapping of the ends of the strip 15 makes this portion of the disc a little heavier than other portions, so that the wheel is unbalanced slightly, to cause the wheel to come to rest with the leg extending vertically, as shown in Figure 1.

As pointed out above, the strip 15 is concentric with the discs 13 and 14 and is situated at a distance inward from the peripheries thereof, so that in addition to its connecting and spacing functions, it is adapted to form the bottoms of wheel propelling air pockets.

15 The pockets are formed around the circumference of the wheel by a strip of paper or cardboard 17 formed with a multiplicity of corrugations, as shown. This strip of paper 17 comprises in succession a stretch 18 in engagement with and adhesively secured to the disc 14, a transverse blade-forming stretch 19, a stretch 20 in engagement with and adhesively secured to the inner face of the disc 13, a transverse blade-forming stretch 21, etc., 20 the arrangement being continued, to form air pockets for the propulsion of the wheel, completely around the periphery thereof.

It will be observed that the weight of the wheel is disposed largely at the outer portion thereof. This is desirable for the reason that the wheel is enabled to acquire a substantial momentum, and hence to rotate for a considerable time after the application of the propelling force has been discontinued.

35 In the embodiment of the invention shown in Figure 6 the structure is generally the same as that already described, but the body member 10' of the connecting member 3', instead of bearing a picture, is made blank and of sufficient size to conceal the wheel, and is provided with an opening 22 through which pictures on the disc 13' may be viewed. The disc in this form is provided with a series of pictures 23 which pass successively behind the opening 22 as the wheel revolves.

40 It will be appreciated, of course, that both discs and both body members may bear pictures or may be arranged as shown in Figure 6, or that one side of the wheel may be used as in Figure 1, and the other as in Figure 6.

55 While I have illustrated and described in detail certain preferred forms of my invention, it is to be understood that changes may be made therein and the invention embodied in other structures. I do not, therefore, desire to limit myself to the specific constructions illustrated, but intend to cover my invention broadly in whatever form its principle may be utilized.

60 I claim:

1. In a toy, in combination, a blow tube, a wheel arranged to be rotated by air expelled from the tube, and means rotatably supporting the wheel from the tube, said wheel comprising a pair of cardboard discs,

a flanged circular paper strip between the discs and adhesively connected to them near the peripheries thereof, and means combined with the discs and strip to form air pockets around the periphery of the wheel.

2. In a toy, in combination, a blow tube, a wheel arranged to be rotated by air expelled from the tube, said wheel comprising a pair of spaced discs, and means forming air pockets around the peripheries of the discs, including a strip of sheet material formed with a multiplicity of corrugations and adhesively secured to the two discs alternately with intervening blade forming strips extending across the space between the discs.

3. In a toy, in combination, a blow tube, a wheel arranged to be rotated by air expelled from the tube, and means rotatably supporting the wheel from the tube, said wheel comprising a pair of spaced discs, and means forming air pockets around the peripheries of the discs, including a circular strip interposed between the discs near the peripheries thereof to form the bottoms of the pockets, and a strip of sheet material formed with a multiplicity of corrugations and secured to the two discs alternately with intervening blade forming stretches extending across the space between the discs.

4. In a toy, in combination, a blow tube, a wheel arranged to be rotated by air expelled from the tube, and means rotatably supporting the wheel from the tube, said wheel comprising a pair of spaced discs, one of which bears a picture, and means forming air pockets around the peripheries of the discs, including a circular strip interposed between the discs near the peripheries thereof, the ends of the strip being overlapped to unbalance the wheel and cause it to come to rest with the picture in a predetermined position.

5. In a toy, in combination, a blow tube, a wheel arranged to be rotated by air expelled from the tube, and means rotatably supporting the wheel from the tube, said wheel supporting means bearing a representation of a human figure, and said wheel comprising a pair of discs, one of which bears a representation of a leg of the human figure, and means forming air pockets around the periphery of the wheel, comprising a circular strip interposed between the discs near the peripheries thereof, the ends of the strip being overlapped in line with the representation on the disc to unbalance the wheel and cause it to come to rest with such representation in upright position.

6. In a whistle toy, in combination, a whistle tube, a wheel arranged to be rotated by air expelled from the tube, means rotatably supporting the wheel from the tube, a reed holder supported in one side of the tube leaving the other side of the tube unobstructed

so that a by-pass of diminished cross section is provided to enable some of the air blown through the tube to pass directly through and impinge upon the wheel, said reed holder being open at one end and closed at the other end and having an opening intermediate its ends in communication with said by-pass whereby air passing through said reed-holder is compelled to join the air blown through said by-pass so that all of the air is delivered against the wheel.

7. In a whistle toy, in combination, a whistle tube, a wheel arranged to be rotated by air expelled from the tube, means rotatably supporting the wheel from the tube, a reed holder mounted within the tube and spaced from one side thereof whereby to provide a direct unobstructed passage for the air blown into the tube to impinge on said wheel, said reed holder having one end open and the other end closed and an opening intermediate its ends, whereby the reed-vibrating air is compelled to rejoin the air blown into the tube and to impinge on the wheel.

25 In testimony whereof I have affixed my signature to this specification.

JOHN M. ABRAMS.
